UNITED STATES PATENT OFFICE.

ALBERT JOSEPH FLEMING, OF SCRANTON, PENNSYLVANIA.

RAILWAY-SWITCH GUARD.

Application filed December 22, 1924. Serial No. 757,544.

The present invention relates to improvements in railway switch guards and more particularly to the improvement in the guard disclosed in a patent issued to Matthew J. McNamara and to James R. Fleming, assignor of one-half undivided interest, under date of August 22, 1922, and numbered 1,426,583.

The present invention has among its principal objects to increase the useful life of the guard; to reduce the cost factor of the guard; and to facilitate the making of repairs when same arise.

Figure 1 is a plan view of a fragment of a railway switch showing in conjunction therewith a guard member constructed and arranged in accordance with the present invention.

Figure 2 is a vertical section of a railway rail and guard member, the section being taken as on the line 2—2 in Figure 1.

Figure 3 is a rear view of the guard member shown in Figures 1 and 2.

Figure 4 is a detail view showing a side elevation of a fragment of a railway rail and a guard member constructed and arranged in accordance with the modified form of the invention.

Figure 5 is a vertical section of a railway rail and guard member, the section being taken as on the line 5—5 in Figure 4.

Figure 6 is a rear view of the guard member shown in Figures 4 and 5.

As seen in the drawings the switch guard embodies a deflector 11, the central portion of which is thickened to form seating shoulders 12 shaped to rest on the chair block 13. The block 13 is shaped at the rear to fit the corner of the junction of the web 14 and the flange 15 of the railway rail with which it is associated.

The deflector 11 has an outwardly inclined extension 16 at the edges thereof. The inner surface extensions are shaped in correspondence with the side of the head 17 of the railway rail and seating portions of the blocks 13. The extremities of the extensions 16 are reduced to a relatively fine edge, the purpose being to receive the flange of the car wheel without shock and to deflect the same by causing it to slide down over the inclined surface of the outer face of the extensions.

The preferred form of the deflectors 11 is that shown in Figures 1 to 3 inclusive of the drawings, wherein the deflector is elongated

and inclined surfaces are formed on the longer sides thereof. When thus constructed the deflectors have a series of bolt holes 18 disposed as best seen in Figure 3 of the drawings in line to receive the fastening bolts 19. The bolts 19 have a threaded end to receive the nut 20, which when set up bears against the deflector to draw the head of the bolt against the web of the railway rail, or against a suitable washer (not shown) placed between the head of the bolt 19 and the web of the rail.

In some cases I prefer to hold the block 13 and deflector 11 in service position by providing a projection 22 on the block 13 and a corresponding recess 23 in the back of the thickened portion of the deflector 11. The engagement between the recess 23 and projection 22 offsets any tendency the block 13 might have or develop, to drift from under the deflector 22.

In the modified form of the invention shown in Figures 4 to 6 inclusive, the deflector 11 is four-sided and is rectangular in shape, each of the edges being chamfered or inclined in simulation to the inclined surfaces of the extension 16 as above set forth. The deflector 11 has a rectangular extension 24 at the back to form the shoulder seats to rest on the block 13, which in the present case is abbreviated in correspondence with the length of the extended portion 24.

It is obvious that when using the modified form of the deflector, the wearing surfaces and the consequent longevity of the deflector is increased. It will also be noted that the perforation 25 with which the modified form of the deflector is provided are disposed in pairs rather than in series, each pair of perforations are spaced apart so as to receive two of the bolts 19 instead of the four shown in Figure 3 of the drawings. The pairs of perforations 25 are disposed as shown in Figure 6 in perpendicular relation.

When disposed in service, the deflectors are bolted to the railway rails immediately in front of the reduced end 26 of the swinging rail 27 of a railway switch. In practice this construction and arrangement results in deflecting or forcing the car wheels laterally out of the path of the extremity of the swinging rail 27. To this end the flange of the car wheel which runs at the inside of the rails rides upon and slides down the inclined surface 16 of the deflector in such manner that when leaving the deflector, the

inside of the flange of the wheel is out of line with the feathered or reduced end 26 of the swinging switch rail 27, in the manner disclosed in the patent above referred to. 5 When, however, one edge of the deflector 11 becomes worn, the deflector is removed and inverted, presenting an unworn surface 16, thus doubling the useful life of the deflector. In the modified form of deflector shown in 10 Figures 4 to 6 inclusive, four inclined surfaces 16, may be placed in service, thereby increasing the useful life of the deflector by four.

Claims:

- 15 1. A railway switch guard embodying a deflector member having a plurality of inclined surfaces for engaging the flange of a railway wheel to shift the same toward the center of a railway track; and means for attaching the same on a railway rail in advance of the reduced end of a swinging switch rail in such manner that any desired one of said inclined surfaces may be placed in operative position.
- 20 2. A railway switch guard embodying a deflector member having a plurality of inclined surfaces for engaging the flange of a railway wheel to shift the same toward the center of a railway track; and means for attaching the same on a railway rail in advance of the reduced end of a swinging switch rail, said means embodying a chair block adapted to rest on the flange of a rail for supporting said deflector member.
- 25 3. A railway switch guard embodying a

deflector member having a plurality of inclined surfaces for engaging the flange of a railway wheel to shift the same toward the center of a railway track; and means for attaching the same on a railway rail in advance of the reduced end of a swinging switch rail, said means embodying a removable chair shaped to fit the railway rail and an extension at the rear of the deflecting member adapted to extend over and rest upon said chair. 40

4. A railway switch guard embodying a deflector member having a plurality of inclined surfaces for engaging the flange of a railway wheel to shift the same toward the center of a railway track; and means for attaching the same on a railway rail in advance of the reduced end of a swinging switch rail, said means embodying a removable chair shaped to fit the railway rail, and an extension at the rear of the deflecting member adapted to extend over and rest upon said chair; and means for preventing the disalignment of said chair and deflecting member. 45

5. A railway switch guard embodying a symmetrical removable deflector member having a plurality of inclined surfaces for engaging the flange of a railway wheel to shift the same toward the center of a railway track, said inclined surfaces being adapted to be successively placed in operative position. 60 65

ALBERT JOSEPH FLEMING.
